CLAMP FOR SCREEN FRAMES

Peyton M. Thompson, Lockport, N. Y., assignor
to Richmond Manufacturing Company, Lock-
port, N. Y., a corporation of New York

Application November 14, 1949, Serial No. 127,090

11 Claims. (Cl. 209—319)

1

This invention relates to sifters and particularly relates to an equalizing hold-down for the stacks of sifters in which a plurality of stacks of superposed screens are mounted for high speed gyration as a unit.

This application is an improvement on the Sifter described and claimed in the co-pending application of David Crampton, Serial No. 144,090, filed February 14, 1950.

It is an object of the present invention to provide a sifter of the type described with an improved mechanism for clamping the stacks of screen frames together and holding them securely to the sifter frame.

A further object of the invention is to provide a sifter of the type described in which the clamping means for the stacks of screen frames is readily accessible and easily operated.

Another object of the invention is to provide means for raising the top frame or cover of each of the stacks of screen frames and supporting the top frame in an elevated position to permit replacement or substitution of screens.

Another object is to provide such a hold-down in the nature of a linkage having a floating connection with its anchorage and capable of moving to exert an equalized pressure on the corners of the stack so that uniform clamping pressure is applied to the corners of the stack as a function of tightening the hold-down.

Another object is to provide guides to insure substantially true vertical movement of the top frames when being elevated or clamped down thereby to insure that each top frame is accurately brought into proper register with its stack of screens as it is lowered.

A still further object of the invention is to provide a simple clamping mechanism which firmly holds each stack of screen frames against vertical motion by rods attached adjacent to the corners of the covers thereof.

Other objects and advantages of the present invention will appear from the following description and drawings in which:

Fig. 1 is a side elevational view of one end of a sifter embodying the present invention.

Fig. 2 is a top plan view of the end of the sifter shown in Fig. 1.

Fig. 3 is a vertical sectional view on the line 3—3 of Fig. 2.

Fig. 4 is an end elevational view of the sifter shown in Fig. 1 with parts broken away the better to show certain structure.

Fig. 5 is a fragmentary enlarged view showing in vertical section the details of the cover clamp-

2

ing mechanism used on the ends of the sifter, this section being taken on the line 5—5 of Fig. 1.

Fig. 6 is a view similar to Fig. 5 showing details of the cover clamping mechanism used between stacks of screen frames, this section being taken on the line 6—6 of Fig. 3.

Fig. 7 is a fragmentary end elevational view showing the arrangement of the port for providing access to the clamping device between the stacks of screen frames.

This application provides improvements in sifter constructions which are particularly useful with high-speed sifters of the type shown and described in the copending application of Peyton M. Thompson, Serial No. 562,753, for High Speed Sifters, filed November 10, 1944, now Pat. #2,511,885, and the improvements have been illustrated as applied to a sifter of that type. The apparatus required for imparting gyratory circular motion to the sifter and a number of other details of sifter construction which are not pertinent to the present invention are not illustrated or described herein. It will be understood that the above mentioned application may be referred to for such details or that, if desired, any other suitable construction may be employed.

The body of the sifter embodying the present invention is shown as of generally square, box-like form and as carrying four stacks of screens, although it will be understood that the invention is applicable to sifters in which a greater or fewer number of stacks of screens are employed. Since the construction of the screen stacks is the same except for the necessary reversal of parts, the same reference numerals will be used to designate similar parts on the two stacks of screens shown in the drawings and on the frame.

The main supporting frame for the sifter of the present invention comprises a pair of horizontal channel beams 20 which are arranged on opposite sides of the sifter and are preferably disposed in a horizontal plane intersecting the center of gravity of the sifter. The channels of the beams 20 face outwardly, and adjacent the center of the sifter are rigidly connected by a pair of horizontally spaced transverse channel beams 22, the ends of which are preferably welded to the side channel beams 20.

To support the main frame for the usual vibratory or gyratory motion in a horizontal plane, each of the ends of the longitudinal side channel beams 20 is supported by a plurality of vertically disposed wooden reeds 24. The upper ends of each group of these wooden reeds 24 are suitably anchored to the ceiling of the room in which the

sifter is housed (not shown) or to other suitable supporting means. The lower ends of each group of reeds 24 are secured to the outer face of one of the longitudinal side channel beams 20 by a block and clamping plate 26 which are held in position and in clamping engagement by screws or bolts 28. As pointed out in the co-pending application above referred to, the connections between the reeds 24 and the main longitudinal side beams 20 of the frame should preferably be at places which lie in a plane intersecting the center of gravity of the sifter, for the reason that greater gyratory speed can be secured and vibration will be minimized.

At spaced intervals along each of the main longitudinal side channels 20 of the sifter frame the reduced upper ends 29 of depending tie rods 30 extend upwardly through the flanges of the beam 20 and are secured to nuts 32 supported on the upper flange of this beam with the shoulders separating the reduced ends 29 and lower portions 31 of the rods 30 in contact with the lower flanges of the beams 20. The lower ends of the tie rods 30 extend through the side angle bars 34 of a supporting platform frame 36. The frame 36 comprises the side angle bars 34, the end transverse angle bars 38 which connect the ends of the bars 34, and intermediate transverse angle bars 40 which connect the side angle bars 34 at places directly below the transverse channel beams 22 of the main frame of the sifter. The platform frame 36 and the platform 42 on the bottom side thereof are supported by nuts 44 at the lower ends of the vertical tie rods 30.

The platform 42, as shown in the drawings, carries at each end intermediate the reeds 24 and the channel beams 20 two stacks of screen frames 46. The inner construction of the screens in frames 46 is not a feature of the present invention. If desired, the screens may be like those shown and described in the copending application above referred to or they may be of any other construction suitable to sift, bolt, separate, screen, or grade the material being handled into different sizes. Holes in the bottom of the platform 42 provide communication with outlet spouts 48 through which the sifted or graded material is withdrawn.

Three of the corners of each stack of screen frames 46 are embraced by vertical angle bars 50, 52, and 54. The vertical angle bars 50 fit into the corresponding corners between the longitudinal channel beams 20 and the transverse channel beams 22 of the main frame of the sifter. The vertical angle bars 52 have their lower ends inside the transverse angle bar 40 of the platform frame and intermediate their lengths are preferably attached as by welding to the transverse channel beams 22 of the main sifter frame. At their upper ends the bars 52 are preferably attached to the transverse angle bars 23 which lie above and parallel to the beams 22 and bars 40 and which are connected at their ends by the longitudinal members 25. The bars 52 embrace, respectively, the adjacent inside corners of the stacks of screen frames 46.

At the outside corners of the stacks of frames 46 which are adjacent to the corners of the platform 42 vertical angle bars 54 are provided, the bars 54 being arranged inside of the main longitudinal channel beams 20 and the platform frame angle bars 34 and 38. The angle bars 50, 52, and 54 may be secured in position by any suitable means. If desired the vertical bars 52 may be permanently fixed in position, as by bolting, welding, or riveting, and the bars 50 can be adjusta-

bly moved toward these bars 52 to clamp the screen frames therebetween by the clamping means shown in the application above referred to.

5 A clamping plate 56 is pivotally mounted at each end of the platform 42. The member 56 comprises a flat face plate 58 which is provided adjacent its lower end with a pair of outwardly extending lugs 60 which are secured to a mounting block 62 by the hinge pin 64 and nut 66. The blocks 62 are preferably welded to the bars 38 of the platform frame 36. The face plate 58 has integrally attached thereto on the rear side thereof a pair of spaced inwardly extending flanges 68. The clamping member 56 is adapted 10 to be swung around a horizontal axis on hinge pin 64. When in normal vertical position the member 56 has the face plate 58 overlapping and flush against the sides of the adjacent stacks of screen frames 46 with the inwardly extending flanges 68 serving to prevent sidewise displacement of the frame 46.

In effect, the clamping member 56 provides a pair of angle bars mounted on a single pivoted plate. The clamping member 56 is provided with 15 a handle 70 and is held in vertical position by a plurality of wing nuts 72 which are secured on the threaded ends of the tie rods 74. The tie rods 74 are secured at their inner ends to a vertical plate 76 which extends transversely substantially the full width of the sifter and is secured to the transverse channel beam 22 and transverse angle bars 23 and 40 by welding or other suitable means. The tie rods 74 pass through the vertical plate 76 and are held there 20 to by nuts 78 screwed on the threaded ends of the tie rods on each side of the plate 76. Tightening of the wing nuts 72 on the tie rods 74 results in the face plate 58 exerting pressure on the corners of the screen frames 46 and drawing them into close engagement with the vertical angle bars 52. Since the sifter is subject to rapid gyratory motion it is essential that the screen frames 46 be firmly clamped in alignment. Clamping of the adjacent sides of the two stacks of frames carried at each end of the sifter is 25 obtained by the clamping members 56 as above described.

To each end of each of the main longitudinal side beams 20 of the main frame of the sifter there is secured a clamping plate 80 which is L-shaped in horizontal section. Each of the L-shaped clamping plates 80 is provided with a pair of vertically spaced, outwardly extending ears 82 which are secured for pivotal movement to the outwardly extending flanges of the adjacent channel beam 20 by means such as a pivot pin or bolt 84. The clamping plates 80 can thus be 30 swung to embrace the corners of the vertical angle bars 54.

Each clamping plate 80 is provided with a lug 60 86 which projects outwardly from the corresponding end of the sifter. Each of the lugs 86 is provided with an upwardly directed slot 88, the slots 88 in the two clamping plates 80 at each end of the sifter being in horizontal alignment 65 and in the same vertical plane. A rod 90 threaded at both ends for the mounting of handwheels 92 is received within the slots 88 with the handwheels on the outer sides of the lugs 86. When the hand wheels 92 are turned on the screw threaded ends of the rod 90 the hubs 93 of said wheels are brought to bear against the lugs 86 and in pulling the lugs together cause the vertical angle bars 54 embraced by the clamping plates 80 to press against the corners of the 70 75

screen frames 46 and thus to clamp the stack of frames securely between the vertical angle bars.

Although the screen frames 46 are clamped between the member 56 and the angle bars 50, 52 and 54 to prevent horizontal shifting with respect to platform 42, it is also necessary to hold the screen frames firmly down against the platform frame 36. By the present invention there is provided mechanism for securely clamping the screen frames 46 downwardly against the platform frame 36 by means attached to the top frame 96 with which each stack of screen frames is equipped.

Each of the top frames 96 is equipped with an inlet spout 98 in the top thereof through which the materials to be sifted or screened are admitted to the rectangular header 100 which is interposed between the top screen frame 46 in each stack and the top frame 96 and preferably projects upwardly above the tops of the angle bars 50, 52 and 54 and the clamping plates 58. The headers 100 provide receptacles within which the material to be sifted or screened collects and from which the material is fed to the series of screens below. If desired, the headers 100 and top frames 96 can be attached or made integral to constitute a unitary structure. On opposite sides of each of the top frames 96 adjacent the corners thereof there are provided pins 102 which extend horizontally outwardly therefrom with the pins 102 on one side of each cover projecting over side beams 20. Mounted on the pins 102 and depending therefrom are elongated rods or draw bars 104 and 106.

A bracket 108, which is L-shaped in vertical cross section, is mounted at each end of the sieve platform adjacent the outer side of each of the stacks of screen frames 46 thereon below the projecting pins 102. The shorter leg 110 of the L preferably extends outwardly from the screen frames and is secured by bolts 112 or other suitable means to the supporting platform frame 36. The longer, vertically extending leg of each of the brackets 108 is provided with a pair of converging diagonal slots 114 which extend inwardly and downwardly from points adjacent the upper corners of said brackets. Associated with each of the brackets 108 is a horizontally disposed draw screw 116 which is threaded substantially throughout its length with the threads on one end thereof being directed oppositely from the threads on the other end. Threadedly mounted on each threaded end of each draw screw 116 is a draw nut or shoe 118. Each of the draw nuts or shoes 118 is provided with a cylindrical extension 120 which passes through one of the slots 114 in one of the brackets 108, so as to have a floating connection therewith, and through the bottom end of one of the draw bars 104, being held in place therein by a spring clip 122. To reduce friction, the cylindrical extensions 120 preferably carry rollers 123 which surround these extensions and ride in the slots 114. The outwardly facing ends of the draw screws 116 are provided with squared portions 124 which are adapted to be engaged by a key or a socket wrench.

At each end of the sifter, between the two stacks of screen frames 46 and behind the face plates 58 there are provided L-shaped brackets 126 substantially like brackets 108. The brackets 126 are equipped with slots 114, threaded draw screws 116 and draw nuts 118 in the same manner as the brackets 108. The draw nuts 118 are connected, respectively, to the lower ends of a

pair of draw bars 104. At the upper end of each of the brackets 126 there is mounted another L-shaped bracket 128 which is secured to the bracket 126 by a pair of bolts 130 passing through the brackets 126 and 128.

Rigidity of the brackets 128 is provided by pairs of sleeves 132 which are mounted on the bolts 130 between the brackets 126 and 128. The brackets 128 are provided like the brackets 108 and 126 with diagonal converging slots 114, threaded draw screws 116, and draw nuts 118, the nuts 118 having extensions 120 with rollers 123 passing through the slots 114 and connected to draw bars 106. The draw bars 104 and 106 are in all respects identical except for length, the bars 106 being shorter than the bars 104 since the bracket 128 with which they cooperate is mounted above the other brackets 108 and 126.

As will be seen from the drawings, by proper rotation of the draw screws 116 the pairs of draw nuts or shoes 118 threadedly mounted thereon will be caused to approach each other. Consequently, the extensions 120 on said shoes or nuts will move downwardly in the converging slots 114 and, through the draw bars 104 and 106, all four corners of each of the top frames 96 will be pulled down, thus securely clamping the screen frames 46 and the header 100 in place and holding the same firmly down on the platform frame 36. Access to the squared ends 124 of the draw screws 116 mounted on the brackets 126 and 128 is obtained by forming a vertically elongated opening 134 in the face plate 58, the vertical elongation of this opening 134 permitting direct access to each of the squared ends 124 of the corresponding draw screws 116, regardless of their elevation at the time. Although the brackets 108 and 126 are illustrated as being mounted on the platform 42, they may be mounted in any other convenient manner. For example, the brackets 108 could be, if desired, mounted on main frame beams 20.

It is desirable to guide the upper end of one of the draw bars 104 or 106 at each side of each stack of screens so that the top frames 96 are constrained to move in a vertical path without lateral displacement or wobbling and so that each top frame is brought down in proper register with its stack of screen frames to fit properly thereon. For this purpose, a guide plate 135 is shown as secured to the upper end of each of the corner angle bars 50 and 52, each of these guide plates being vertically disposed and projecting alongside the corresponding stack of screen frames 46 and alongside the adjacent draw bar 104 or 106. Each of these guide plates 135 is provided with an inclined slot 136 which inclines in the same direction as the slot 114 associated with the same draw bar but at a lesser angle to the vertical. Each of these guide slots 136 guides a guide pin 138 projecting laterally from the adjacent draw bar 104 or 106 into the guide slot. It will be seen that as the lower end of each draw bar so guided by its guide plate 135 is moved vertically and laterally in following its slot 114, its upper end is also moved vertically and laterally by the guide slot 136, the lateral movement of the upper end of the draw bar being less than its upper end as determined by the difference in distance of the slots 136 and 114 from the pivots 102. By so guiding the upper ends of a pair of draw bars associated with each stack of screen frames, the top frame 96 thereof is constrained to move in a substantially true vertical path without wobbling or lateral displacement and the top frame is brought down in accurately positioned register with the

stack of screen frames so as to fit properly thereon without reaching up manually to position the top frame as it is being clamped down.

The operation of the improved clamping mechanism of the present invention is as follows. Assuming that the sifter is stationary and that it is desired to change or replace some or all of the screens in the stacks of screens 46, the following procedure would be followed.

The handwheels 92 on the rod 90 would be unscrewed sufficiently to permit the rod to be raised from the slots 88 in the lugs 86. The rod 90 would be removed and the clamping plates 80 would be swung outwardly and back on the pivoted pins or bolts 84. The angle bars 54 would then be removed. The angle bars 50 would then be released from inward clamping engagement with the stacks of screens, this clamping mechanism not being shown. Wing nuts 72 would be unscrewed and the clamping member 56 would be swung outwardly and downwardly on hinge pin 64. A suitable wrench or key would then be applied to the squared ends 124 to turn the draw screws 116 associated with the brackets 108, 126 and 128 in a direction to cause the draw nuts 118 to be moved apart and upwardly in the slots 114, thus raising the top frames 96. The headers 100 and any of the screen frames 46 can then be withdrawn and other frames substituted therefor.

When the desired substitution of screens has been made, the clamping member 56 is raised into vertical position, with the rearwardly extending flanges 68 passing between the stacks of screen frames 46, and the wing nuts 72 are applied to the threaded ends of the tie rods 74. The vertical angle bars 54 are next placed in position embracing the outside corners of the stacks of screen frames and the clamping plates 80 mounted on the channel beams 20 are swung around into position with the lugs 86 extending forwardly and the slots 88 in alignment. The rod 90 carrying the handwheels 92 is thereupon placed in the slots 88. The draw screws 116 are then rotated in the opposite direction with the result that the nuts 118 will be drawn together and downwardly in the slots 114 and the draw bars 104 and 106 will be moved downwardly to seat the top frames 96 and draw them firmly down against the screen frames 46. In such movement the guide pins 138 on the upper ends of a pair of the draw bars 104 and 106 associated with each stack of screen frames follow their guide grooves 136 in the guide plates 135 and hence the top frame 96 is lowered in a substantially true vertical path and is brought into accurate register with the screen frames 46 to seat accurately thereon. The assembly will consequently be clamped firmly against the platform 42.

It will particularly be noted that the holddown of the present invention serves to equalize the clamping pressures on the corners of the stacks by virtue of the floating connection of the shoes or nuts 118 with the slotted plates 108 or 128. Thus assuming that, say, the upper right hand corner of the stack of screen frames as viewed in Fig. 1 is higher than the upper left hand corner, on turning the screw 116 the shoe or nut 118 at the left would be drawn further down its slot 114 than the shoe or nut 118 on the right and the screw 116, in the final position, would be at an angle to the horizontal, inclining downwardly toward its headed end. By virtue of this distortion of the linkage due to its floating anchorage, the holddown would apply the same

downward pressure at the one corner as the other in spite of the fact that one corner is higher than the other, as assumed. Accordingly the holddown applies equalized clamping pressures to the corners of the top frames of the stack or stacks of screen frames.

It will be noted from the foregoing description that the clamping means employed to prevent horizontal and vertical movement of the stacks of screen frames 46 with respect to the platform 42 is simple and easily operated. It will also be noted that the stacks are clamped together as masses so connected to the main frame as to avoid irregular stresses thereon. Such stresses are undesirable as crystallization and failure of the frame may result from them. Another important feature of the invention as described above is the positive raising of the top frames 96 from the stacks of screen frames 46 by rotation of the draw screws 116. This does away with the necessity of providing auxiliary support for the top frames during the changing of screens or the manual lifting thereof to remove or replace them.

In the foregoing specification, there has been described one embodiment of the present invention as applied to a sieve of the general type shown and described in the said co-pending application, Serial No. 562,753. It will be understood, however, that the invention is capable of application to other sifter constructions and that modification to adapt the invention for such use is within the spirit of the present invention. It will be further understood that numerous modifications of the details of construction shown and described herein may be made without departing from the spirit of the invention. Accordingly, it is desired that the invention should not be limited by the foregoing description and the accompanying drawings, but is to be accorded the full range of equivalents comprehended by the accompanying claims.

I claim:

1. An equalizing holddown for a stack of rectangular screen frames mounted on a support and said stack having a top frame, comprising at least one pair of elongated tension members at each of two opposite sides of said stack and severally connected at their upper ends to the corners of said top frame to swing parallel with said opposite sides of said stack, a guide member at each of said opposite sides of said stack and secured to said support below each pair of tension members and having a pair of converging surfaces inclined with reference to the horizontal and extending generally parallel with said opposite sides of said stack, a pair of independently floating shoes severally slidably secured to each pair of said surfaces for movement therealong independently of each other, means connecting the lower end of each of said tension members with a corresponding one of said shoes, and a pair of floating, manually operable screws each connecting the shoes of each pair and arranged to positively move said shoes of each pair toward and from each other along said surfaces thereby to raise and lower said top frame and to apply equalized downward pressures at said corners of said top frame against said stack of screen frames.

2. An equalizing holddown as set forth in claim 1 wherein each of said guide members is in the form of an upstanding plate mounted on said support, and wherein each said pair of converging surfaces are provided by upper and lower

surfaces of slots in each of said plates, and wherein a roller is rotatably secured to each of said shoes and rides in a corresponding slot.

3. An equalizing holddown as set forth in claim 1 wherein each of said guide members is in the form of an upstanding plate mounted on said support and wherein each said pair of converging surfaces are provided by the upper and lower surfaces of slots in each of said plates, wherein each of said shoes is in the form of a nut having a stud on which a roller is rotatably mounted with said rollers severally riding in said slots, wherein each said screw is threaded in a corresponding pair of said nuts, and wherein each of said nuts is arranged on the side of its tension member remote from its guide plate.

4. An equalizing holddown for two closely spaced parallel stacks of rectangular screen frames mounted on a common support and each of said stacks having a top frame, comprising a tension bar connected at its upper end to each of the four corners of each of said top frames to swing parallel with the space between said stacks and the lower end of each of said tension bars being disposed closer to said support than to said top frame, two pairs of said tension bars being arranged in said space with each pair close to the side of a corresponding stack and the other two pairs being each arranged close to the face of the corresponding stack opposite said space, a shoe pivotally secured to the lower end of each of said tension bars, a plurality of guide members mounted on said support severally below and projecting upwardly toward a corresponding pair of said tension bars, said guide members being provided below each tension bar with a slot having upper and lower opposing faces engaging, respectively, the upper and lower faces of a corresponding one of said shoes, the pair of slots associated with each pair of tension bars inclining in opposite directions with reference to each other and constraining each pair of tension bars and shoes to move both upwardly and downwardly relative to said support independently of one another in response to horizontal movement of each pair of shoes toward and from each other, and four manually operable generally horizontal screw members arranged parallel with the space between said stacks and each having opposite ends operatively connected with the corresponding pair of shoes to move said pair of shoes horizontally toward and from each other thereby to raise and lower each top frame and to apply equalized downward pressures at said corners of said top frame against said stack of screen frames.

5. An equalizing holddown for two closely spaced parallel stacks of rectangular screen frames mounted on a common support and each of said stacks having a top frame, comprising a tension bar connected at its upper end to each of the four corners of each of said top frames to swing parallel with the space between said stacks and the lower end of each of said tension bars being disposed closer to said support than to said top frame, two pairs of said tension bars being arranged in said space with each pair close to the side of a corresponding stack and the other two pairs being each arranged close to the face of the corresponding stack opposite said space, a nut pivotally secured to the lower end of each of said tension bars, the threaded bores through said nuts being generally horizontal and parallel with the space between said stacks, a roller rotatable on each stud, a plurality of guide members mounted on said support severally below and projecting upwardly toward a corresponding pair of said tension bars, said guide members being provided below each tension bar with a slot having upper and lower opposing faces engaging, respectively, the upper and lower faces of a corresponding one of said rollers, the pair of slots associated with each pair of tension bars inclining in opposite directions with reference to each other and constraining each pair of rollers, tension bars and nuts to move both upwardly and downwardly relative to said support independently of each other in response to horizontal movement of each pair of nuts toward and from each other, and four manually operable generally horizontal screw members arranged parallel with the space between said stacks and each having opposite ends screwed into the corresponding pair of nuts and formed to move said pair of nuts horizontally toward and from each other thereby to raise and lower each top frame and to apply equalized downward pressures at said corners

the lower end of each of said tension bars, a plurality of vertical guide plates arranged generally parallel with said space and mounted on said support severally below and projecting upwardly toward a corresponding pair of said tension bars, said guide plates being provided below each tension bar with a slot having upper and lower faces engaging, respectively, the upper and lower faces of a corresponding one of said rollers, the pair of slots associated with each pair of tension bars inclining in opposite directions with reference to each other and constraining each pair of rollers, tension bars and nuts to move both upwardly and downwardly relative to said support independently of one another in response to horizontal movement of each pair of nuts toward and from each other, and four manually operable generally horizontal screws arranged parallel with the space between said stacks and each having opposite ends screwed into the corresponding pair of nuts and formed to move said pair of nuts horizontally toward and from each other thereby to raise and lower each top frame and to apply equalized downward pressures at said corners of said top frames against said stacks of screen frames.

6. A structure as set forth in claim 5 wherein each of said nuts is arranged on the side of its tension arm remote from its guide plate.

30 7. An equalizing holddown for two closely spaced parallel stacks of rectangular screen frames mounted on a common support and each of said stacks having a top frame, comprising a tension bar connected at its upper end to each of the four corners of each of said top frames to swing parallel with the space between said stacks and the lower end of each of said tension bars being disposed closer to said support than to said top frame, two pairs of said tension bars being arranged in said space with each pair close to the side of a corresponding stack and the other two pairs each arranged close to the face of the corresponding stack opposite said space, a nut having a horizontal stud pivotally fitted in an opening at the lower end of each of said tension bars to permit the nut to swing about a generally horizontal axis generally parallel with the normal pivot axes of the upper ends of said tension bars, the threaded bores through said nuts being generally horizontal and parallel with the space between said stacks, a roller rotatable on each stud, a plurality of guide members mounted on said support severally below and projecting upwardly toward a corresponding pair of said tension bars, said guide members being provided below each tension bar with a slot having upper and lower opposing faces engaging, respectively, the upper and lower faces of a corresponding one of said rollers, the pair of slots associated with each pair of tension bars inclining in opposite directions with reference to each other and constraining each pair of rollers, tension bars and nuts to move both upwardly and downwardly relative to said support independently of each other in response to horizontal movement of each pair of nuts toward and from each other, and four manually operable generally horizontal screw members arranged parallel with the space between said stacks and each having opposite ends screwed into the corresponding pair of nuts and formed to move said pair of nuts horizontally toward and from each other thereby to raise and lower each top frame and to apply equalized downward pressures at said corners

11

of said top frames against said stacks of screen frames.

8. A structure as set forth in claim 7 wherein each roller has an extension fitting the opening in the lower end of the corresponding tension bar.

9. A structure as set forth in claim 4 wherein a second guide member is fixed to said common support and is disposed adjacent the upper ends of at least one tension bar of each stack and wherein said second guide member constrains the tension bar associated therewith against lateral movement with reference to said stack to guide said top frame in its upward and downward movement relative to said stacks.

10. An equalizing holddown for the adjacent corners of two closely spaced parallel stacks of rectangular screen frames mounted on a common support and each of said stacks having a top frame, comprising a tension bar connected at its upper end to each of the adjacent corners of said top frames to swing parallel with the space between said stacks and the lower end of each of said tension bars being disposed closer to said support than to said top frames, two pairs of said tension bars being thereby arranged in said space with each pair close to the side of a corresponding stack, a shoe pivotally secured to the lower end of each of said tension bars, at least one guide member mounted in said space on said support and projecting upwardly toward said pairs of tension bars, said guide member being provided below each tension bar with a slot having upper and lower opposing faces engaging, respectively, the upper and lower faces of a corresponding one of said shoes, the slots associated with each pair of tension bars inclining in opposite directions with reference to each other and positively constraining each pair of tension bars and shoes to move both upwardly and downwardly relative to said support in response to horizontal movement of each pair of shoes toward and from each other, and a pair of manually operable generally horizontal screw members arranged parallel with the space between said stacks and each having opposite ends operatively connected with the corresponding pair of shoes to move said pair of shoes horizontally toward and from each other thereby to raise and lower the corresponding top frame relative to its stack and to apply equalized downward pressures at said corners of said top frame against said stack of screen frames.

11. An equalizing holddown for the adjacent corners of two closely spaced parallel stacks of rectangular screen frames mounted on a common support and each of said stacks having a top frame, comprising a tension bar connected at its upper end to each of the adjacent corners of said top frames to swing parallel with the space between said stacks and the lower end of each

12

of said tension bars being disposed closer to said support than to said top frames, two pairs of each tension bars being thereby arranged in said space with each pair close to the side of a corresponding stack, a nut having a horizontal stud pivotally fitted in an opening at the lower end of each of said tension bars to permit the nut to swing about a generally horizontal axis generally parallel with the normal pivot axes of the upper ends of said tension bars, the threaded bores through said nuts being generally horizontal and parallel with the space between said stacks, a roller rotatable on each stud, at least one guide member mounted in said space on said support and projecting upwardly toward said pairs of tension bars, said guide member being provided below each tension bar with a slot having upper and lower opposing faces engaging, respectively, the upper and lower faces of a corresponding one of said rollers, the slots associated with each pair of tension bars inclining in opposite directions with reference to each other and constraining each pair of rollers, tension bars and nuts to move both upwardly and downwardly relative to said support independently of each other in response to horizontal movement of each pair of nuts toward and from each other, and a pair of manually operable generally horizontal screws arranged parallel with the space between said stacks and each having opposite ends screwed into the corresponding pair of nuts and formed to move said pair of nuts horizontally toward and from each other thereby to raise and lower the corresponding top frame and to apply equalized downward pressures at said corners of said top frames against said stack of screen frames.

PEYTON M. THOMPSON.
